L. E. Thomas ^{ATTORNEY}

UNITED STATES PATENT OFFICE.

LLOYD E. THOMAS, OF DETROIT, MICHIGAN.

COMBINED BADGE AND DETACHABLE WATCH-GUARD.

1,389,711.

Specification of Letters Patent. Patented Sept. 6, 1921.

Application filed May 10, 1920. Serial No. 380,368.

To all whom it may concern:

Be it known that I, LLOYD E. THOMAS, a citizen of the United States, residing at Detroit, county of Wayne, State of Michigan, have invented a certain new and useful Improvement in Combined Badges and Detachable Watch-Guards, and declare the following to be a full, clear, and exact description of the same, such as will enable others skilled in the art to which it pertains to make and use the same, reference being had to the accompanying drawings, which form a part of this specification.

My invention relates to a coat watch chain, shown in the accompanying drawings and more particularly described in the following specification and claims.

One object of this invention is to provide a coat watch chain adapted to be worn with a fraternity button, emblem or other like device as usually secured in the button-hole of a coat lapel.

A further object is to provide means whereby the chain may be interchangeably or alternately worn with the emblematic button of any of a number of organizations of which the owner may be a member.

A further advantage offered by this invention is that jewelers or other storekeepers selling watch chains may quickly assemble any desired chain with the emblematic button of any organization to meet the requirements of the prospective customer.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawings forming part of this specification:

Figure 1 is a view of a fraternity button supported in a coat lapel showing the coat chain as it would appear when worn therewith.

Fig. 2 is a detail elevation of a fragment of a coat chain attached to a washer or ring

adapted to encircle the post of the button between the latter and the usual "nut" employed to secure the button to the coat.

Fig. 3 is a cross-sectional view through the button,—the chain ring or washer,—the coat lapel and the securing nut.

Referring now to the letters of reference placed upon the drawings:—

A, denotes a fraternity button or like device provided with the usual screw-threaded post B designed to extend through the coat lapel C, to be secured in position by a nut D located beneath the coat lapel.

E, is a washer or ring, to which is secured a chain F, of proper length engaging a watch (not shown).

The washer E, is sleeved upon the post B beneath the button, and may be placed either above or below the coat lapel as fancy dictates.

Having pointed out the several parts by reference letters it will be apparent that the chain may be easily and quickly assembled with any particular button, or may be detached from the button in use and worn with any other emblematic button desired.

Having thus described my invention what I claim is:—

1. In a device of the character described, a button having a rearwardly projecting post adapted to extend through a coat lapel, a washer loosely sleeved upon said post, a chain secured to the washer, and means adapted to engage said post to secure the washer against dislodgment from the post.

2. The combination of a lapel button having a rearwardly projecting screw threaded post adapted to extend through a lapel, a chain provided with an annulus at one end adapted to loosely encircle said post at the rear of the button, whereby it is concealed from view, and a nut engaging said post to secure the button to a lapel and the annulus against displacement.

In testimony whereof, I sign this specification in the presence of two witnesses.

LLOYD E. THOMAS.

Witnesses:

S. E. THOMAS,
EDWIN R. MONNIG.
